UNITED STATES PATENT OFFICE.

ERNST G. APPLETON, ALBERT C. FISCHER, AND RAYMOND MOONEY, OF CHICAGO, ILLINOIS, ASSIGNORS TO ROACH-APPLETON MANUFACTURING COMPANY, OF CHICAGO, ILLINOIS, A CORPORATION OF ILLINOIS.

EXTENSION LAMP.

Application filed November 19, 1923. Serial No. 675,468.

This invention relates to a new and improved electric extension lamp and more particularly to a housing and reel control for lamps of this character.

5 Extension lights of this type comprise a housing adapted to be associated with a vehicle instrument board or similar support, a reel for holding the conducting cable and means for retaining the lamp itself in its 10 normal position in the housing. It is desirable to provide means for holding the lamp firmly but yieldingly in the housing and to provide means whereby the reel may readily pay out and retract the conductor 15 wiring.

It is an object of the present invention to provide a new and improved extension lamp housing assembly having efficient lamp holding and reel control means.

20 It is a further object to provide a housing of this character in which the housing parts are provided with interfitting parts adapted to facilitate assembly.

It is also an object to provide a housing 25 having means adapted to firmly but yieldingly retain a lamp member in position therein.

It is an additional object to provide a 30 ratchet reel control having means for placing the ratchet into or out of operation.

Other and further objects will appear as the description proceeds.

We have illustrated a preferred embodiment of our invention in the accompanying drawings, in which—

Figure 1 is a face view of the lamp housing assembly;

Figure 2 is a view of Figure 1 as seen from the left;

40 Figure 3 is a view of Figure 1 as seen from the right;

Figure 4 is a view of Figure 1 as seen from above;

45 Figure 5 is a view on an enlarged scale similar to Figure 2 but with the side of the casing removed;

Figure 6 is a section taken on line 6—6 of Figure 5;

50 Figure 7 is a view similar to Figure 3 but with the inner side of the case and the reel removed;

Figure 8 is a fragmentary section taken on line 8—8 of Figure 7; and

Figure 9 is a fragmentary section taken on line 9—9 of Figure 7.

The housing comprises the front member 11 which is removably secured to the side members 12 and 13 by means of screws 14 passing through perforations in the flanges 12' and 13' formed on the forward edges of the members and into the member to which the housing is secured as shown in Figures 2, 3 and 4. This front member 11 is provided with the inturned edges 11' which enclose the edges of the flanges 12' and 13' of the side members and with the flanges 11^a which enclose the forward edges of the housing body portion 15.

The body portion 15 of the housing is curved to form the top, bottom and rear of 70 the housing. The side 12 is provided with slots 16 through which are passed ears 17 formed integral with the member 15. Similar ears 18 are passed through slots 19 in the side member 13.

The axle 20, as best shown in Figure 6, extends through openings in the side members 12 and 13. The axle is provided upon its end extending through side 13 with the squared portion 21 over which is fitted an 80 adjusting key 22. This key is held in place upon the axle by means of the screw 23 which is threaded into the axle. The side member 13 of the housing is provided with the struck-up arms 24, either of which is 85 adapted to engage the key 22. The opposite end of the axle 20 has secured thereto the screw 25 which serves to prevent axial displacement of the axle relative to the side 12 and also to retain in place the end of the 90 conducting wire 77.

The reel 26 is fitted upon the axle 20 in such manner as to rotate freely thereon. The end plate 27 of the reel is provided with the overhanging rim 28 which encloses a 95 spiral spring 29. The inner end of this spring is secured to the axle 20 by the pin 30. The outer end of the spring is secured to the flange 28 by the rivet 31. The cotter pin 32 is passed through the axle 20 and engages the end plate 33 of the reel to prevent 100 axial movement of the reel upon the axle 20.

The end plate 33 is provided with a short arcuate recess 34 in which is fitted the insulated element 35. A similar insulated element 36 is located upon the opposite side 5 of the member 33 and the eyelets 37 secure the two pieces of insulation in place. These eyelets are out of contact with the metallic portion 33 of the reel, and serve to secure against the insulated member 36 the inner 10 end of a contact spring 38. The outer end of this contact spring 38 is adapted to bear against a contact ring 39 as shown in Figure 7.

The two layers of insulation 40 and 41 are 15 secured to the side 12 by means of the tongues 42 which are struck up from the side 12 and pass through the insulation and are crimped upon it as shown in Figure 9. These pieces of insulation 40 and 41 extend 20 over beyond an opening in the side 13 of the casing through which opening is passed the screw 43. This screw engages an extension 44 of the contact ring 39 and serves to aid in maintaining that ring in place. The ring 25 is also maintained in place by fingers 45 which are bent down from the ring over the edge of the piece of insulation 41 and against the face of the piece of insulation 40.

The screw 43 extends outwardly through 30 the side 12 of the casing as shown in Figure 2 and carries the nut 46 which retains in place the fuse clip 47 supported upon the insulating plate 48. The co-operating fuse clip 49 is secured in place by means of bolt 50 and nut 51, the bolt 50 also passing through the plate 48 and side 12. The clips 47 and 49 carry the fuse 52. The screw 50 is surrounded, where it passes through the side 12 of the casing, by the insulating collar 53 so that it is out of electrical contact 35 with the casing.

The reel 26 carries the double conducting wire 54 which is connected to the lamp body 55, which body 55 is removably fitted within the socket member 56 carried in an opening 45 in the face plate 11. The retaining member 57 is screwed to the collar 56 and is provided with a spring finger 57' adapted to engage a groove 58 in the lamp and yieldingly retain the lamp in position in the 50 socket member.

One conductor element has its end away 55 from the lamp passed through one of the eyelets 37 and soldered to the contact spring 38 at 59, as shown in Figure 5. The similar end of the other conductor is passed through the opening 60 in the reel and is soldered to the face of the reel member 33 at 61 as also 60 shown in Figure 5.

As best shown in Figure 5, the reel end 65 plate 33 has its outer edge provided with serrations 62 which form ratchet teeth. The dog 63 is pivoted upon pin 64 passing through side 13 of the casing. This dog has an inturned end 65 adapted to engage the

radial edges of the serrations 62. The 70 spring 66 is riveted to the casing body member 15 at 67 and has a free end engaging the portions 65 of the dog to urge it into engagement in the ratchet.

The slide 68 is provided with the elongated slot 69 through which passes the pivot pin 75 64. This slide is located between the wall 13 and the dog 63. The slide has an upturned portion 70, one edge of which is adapted to co-operate with the cam surfaces 80 71 and 72 on the dog. The operating plunger 73 is secured to the portion 70 and extends through the sleeve 74 which is secured in place in the face plate 11 by means of nut 75.

The electrical circuit of the lamp passes from a lead wire 76 shown in Figure 2 which is connected to the bolt 50 under the nut 51. It passes then through the fuse 52 to the bolt 43 which is insulated from the casing 12. As shown in Figure 8, the inner end of this bolt 43 is in contact with the portion 44 of the contact ring 39 which ring is therefore electrically connected to the wire 76.

The contact spring 38 engages this ring 95 39 and passes the current to the conductor which is soldered to the spring 38 at 59 as shown in Figure 5. The current passes through this conductor and through the bulb which is not shown and back through the 100 second conductor to the reel to which this conductor is soldered at 61. The reel is electrically in contact with the axle 20 and thus with the casing. The return wire 77 of the circuit is connected under the screw 25 fitted in one end of the axle. If a one-wire system is used, the casing may be grounded in any convenient manner instead of connecting the wire 77 as shown.

When it is desired to use the light in its 110 extended position, the member 55 carrying the bulb is withdrawn from the socket 56, the conductor 54 paying out from the reel. This causes a rotation of the reel and compression of the spring 29. Retraction of the conducting wire by reverse rotation of the reel is prevented by the engagement of the dog 63 with the serrations 62 on the reel. When it is desired to retract the wire the plunger 73 is thrust inwardly and the portion 70 engages the cam surface 71 on the dog, swinging it out of engagement with the reel. The portion 70 then catches on the cam surface 72 and maintains the dog out of engagement with the reel until the plunger is again 120 drawn outwardly.

The socket member 56 receives the lamp member and normally maintains it in fixed position in the housing. The spring finger 57' retains it yieldingly in place and yet 130 permits its ready and rapid removal.

The inturned edges of the face plate and their relation to the edges of the housing body are of particular utility in causing the

housing body to be easily located with regard to the face plate to bring the screw receiving holes of the two elements in registration so that the screws may be inserted to secure 5 the parts together and in place upon the support.

We have shown one particular embodiment of our invention by way of illustration but we contemplate such changes and modifications as come within the scope of the appended claims.

We claim:

1. In a housing for an electric extension light, a main housing portion having an open 15 side and perforated flanges located adjacent said open side, a removable face plate adapted to close said open side having perforations adapted to register with the flange perforations and having inturned edges on all 20 sides adapted to enclose the flanges and to maintain the parts in registering relation.

2. An electric extension light comprising a housing, an axle supported therein, a reel fitted on said axle, a spring connecting the 25 reel and axle and tending to rotate the reel in one direction, a conductor wound on the reel and tending when withdrawn therefrom to rotate the reel in the opposite direction, a

series of ratchet teeth upon the reel, a dog adapted to engage said teeth, a cam surface 30 formed on said dog, and a plunger having a portion adapted to engage said surface to move the dog out of engagement with the ratchet teeth.

3. An electric extension light comprising a 35 housing, an axle supported therein, a reel comprising end plates and a central portion fitted on said axle, a spring connecting the reel and axle and tending to rotate the reel in one direction, a conductor wound on the 40 reel and tending when withdrawn therefrom to rotate the reel in the opposite direction, a series of ratchet teeth formed in the periphery of one of the reel end plates, a spring 45 pressed dog adapted to engage said ratchet teeth, cam surfaces on said dog, and a plunger having a portion adapted to engage one of said cam surfaces to move the dog against the spring out of the path of the ratchet teeth and to engage another of said surfaces 50 to maintain the dog in the out position.

Signed at Chicago, Illinois, this 16th day of Nov., 1923.
